UNITED STATES PATENT OFFICE.

ISRAEL L. LANDIS, OF LANCASTER, PENNSYLVANIA.

FASTENING DEVICE FOR GUTTERS AND PAVEMENTS.

SPECIFICATION forming part of Letters Patent No. 374,685, dated December 13, 1887.

Application filed October 26, 1887. Serial No. 253,390. (No model.)

To all whom it may concern:

Be it known that I, ISRAEL L. LANDIS, a citizen of the United States, residing at Lancaster, in the county of Lancaster and State of Pennsylvania, have invented certain new and useful Improvements in Fastening Devices for Gutters and Pavements; and I do hereby declare the following to be a full, clear, and exact description of the invention, such as will enable others skilled in the art to which it appertains to make and use the same.

The object of this invention is to provide gutters consisting of blocks or bricks built in the form of an inverted arch with locking devices which will keep them in such form and hold them securely to the curb of the sidewalk or the blocks of the roadway, or both. To effect this object I employ angular pieces of metal, preferably castings, which fit upon the bricks of the gutter and the sidewalk-curb or fixed blocks of the roadway and lock the bricks of the gutter against displacement. These locking pieces or sections of metal are engaged with each other, so as to form an unbroken facing of metal covering the angle formed by the curb and gutter or by the gutter and the nearest roadway-block.

In the accompanying drawings, Figure 1 represents a perspective view of part of a gutter provided with such a facing of locking-pieces on the sidewalk side. Fig. 2 represents a vertical transverse section through the same. Fig. 3 represents two of the interlocking sections slightly separated to show the parts which engage. Fig. 4 represents, on a smaller scale, in vertical transverse section, a gutter provided with two modified forms of the locking-pieces. Fig. 5 represents a similar view of a gutter provided with two other modified forms of locking-pieces. Fig. 6 represents a similar view of a gutter provided with two other modified forms of locking-pieces. Fig. 7 represents a similar view of a gutter provided with two other modified forms of locking-pieces.

In most of the figures showing the gutter the curbstone or brick and at least one block of the roadway are also shown.

The same letters designate corresponding parts in the several figures.

A designates the curbstone at the outer edge

of a sidewalk. Of course brick or any other suitable substance may be substituted.

B designates the blocks of the roadway.

C designates a gutter composed of bricks arranged in the form of an inverted arch, presenting upward a practically regular transversely-curved surface. At the angle formed by the said gutter and the said curbstone or the nearer blocks, B, of the roadway a series of locking-pieces, D, are located. As shown in the several views above mentioned, these may vary widely in form; but each has such an angular shape as will cause it to fit on the faces of the bricks and the curbstone or roadway-blocks in such wise as to hold the gutter in position as an entirety. As shown in Figs. 1, 2, and 3, each locking piece or section D is provided with a broad flange, D', presenting a curved face obliquely upward. At the back of this are two flat faces, d d', arranged at an angle to each other, the former being vertical when in position for use and fitting against the inner face of the curbstone A, while the face d' fits against the proximate upper face of the nearest brick of the gutter.

Between the curbstone and the gutter the body D' of the locking-piece extends obliquely downward. Its upper part is bent and flattened to present on its upper side a face, d², fitting the flat bottom of the curbstone. The lower part of said body D' fits on the opposite side against the proximate side of the nearest brick of the gutter for the greater portion of the length of said brick. At the lower end of said body D' of the locking-piece a lateral flange, d³, fits under said brick. The two proximate corners of said curbstone and brick are received, respectively, into the angle formed by faces d d² and the angle formed by face d' and a small face, d⁴, of body D', which latter face also fits against the side of said brick. These faces d d² d³ d⁴, with the lower part of body D' and the flange d³, effectually hold said brick in place, since both it and the curbstone are grasped thereby. This will ordinarily suffice to prevent the displacement of any of the bricks forming the inverted arch of the gutter; but for greater security I sometimes would prefer to use a similar locking-piece on the opposite side of the latter, as illustrated in some of the other figures of the drawings.

- The locking-pieces D aforesaid (see Fig. 3) are constructed to engage or interlock with each other, end for end, by means of projections and recesses, which may be greatly varied.
- 5 As shown in said figure, one section has on its end two projecting wings, x x' , forming an angle with each other, while the proximate end of the other section has similarly-arranged recesses z z' , which receive said wings. The latter section has also a plate or wing, z' , on the side opposite to x' , and these two wings, x' z' , fit against the bodies D' of the respective sections, on opposite sides thereof. The locking-pieces D, thus engaged with each other 15 throughout the length of the series, present a continuous guard or cover of metal over the angle between the gutter and the curbstone or brick at the edge of the sidewalk.
- In Fig. 4 I have shown, on the right side, a 20 modified form of locking-piece, D, having its upper end provided with a lateral flange, m , which fits on the top of the curbstone A, and its lower end bifurcated, one fork, m' , fitting against the inclined face of the nearest brick of 25 the gutter, while the other fork is bent at right angles; one part, m^2 , fitting against the bottom of said curbstone, and the other part, m^3 , extending therefrom across to said brick. The body of said locking-piece fits against the side 30 of said curbstone. On the other side said gutter is provided with another modified form of fastening-piece D, consisting of a curved plate with flat rear faces fitting against the nearest block B of the roadway and the two proximate 35 bricks of the gutter. It has rearward wings, n n' , which extend through the cracks between said blocks C and the first brick and between the latter and the second brick. These wings fit against the sides of the bricks, as shown.
- 40 Wing n has a lateral flange, n^2 , extending to block B, to aid in locking the gutter-bricks in place.
- In Fig. 5, the locking-piece D on the right side has likewise two wings extending rearward. 45 They are at such a distance from each other as to leave space for a considerable amount of sand, w , or other loose material between them. These wings (marked o o') fit, respectively, against the under side of the curbstone 50 and the side nearest it of the nearest brick. The body of said locking-piece covers the sand w and fits against the inner face of the curbstone and said brick. On the left side is another locking-piece having a single rearward 55 wing, p , and a shoulder, p' , formed thereon, which fits against the under side of a roadway-block, B. The other side of said wing fits against the side of the nearest brick of the gutter. In this, as in all the other instances 60 given, either locking device being used for either side of the gutter, and any brick or block being the equivalent of the curbstone or roadway-block.

On the right side of Fig. 6 is a locking-piece like the letter K, having rearward wings, q q' , 65 used like wings o o' , already described. A lateral terminal extension, q^2 , of wing q' extends behind the brick to which said wing is applied. The locking-piece on the opposite side of said figure differs but little from this last, 70 except that the wings q q' are united, and the latter has an additional direct extension, q^3 , at its rear end entering the sand w .

Fig. 7 shows on the right side a locking-piece having a thick head notched at r to receive the proximate lower corner of the curbstone, the said locking-piece also fitting against the front and side of the nearest brick of the gutter and having at its rear end a cross-piece, r' , which fits against the rear of said brick. 75 Another brick may be fitted obliquely end-wise between this locking-piece and the curbstone. The locking-piece at the other side of said figure has a notch, r , at its upper end, like the above, and a notch, r^2 , at its lower 80 end, which fits similarly on the nearest brick. This locking-piece has no extension to the rear of said brick, and may be long enough to span a considerable interval of sand or other filling.

Having thus described my invention, what 90 I claim as new, and desire to secure by Letters Patent, is—

1. A gutter composed of brick-work arranged in an inverted arch, in combination with a curbstone, brick, or block of the sidewalk or roadway, and a locking-piece fitting on said curbstone and on one or more of the 95 bricks of said gutter, for the purpose set forth.

2. A metallic locking-piece having faces to fit against the gutter and pavement and lock 100 the former in place.

3. A series of locking-pieces having recesses and projections engaging end for end and faces which fit against the curb or roadway blocks and the gutter to lock the latter in place. 105

4. The locking-piece D, having faces d d' , which fit against the front and bottom of the curbstone, additional faces, d^2 d^3 , which fit against the corresponding parts of the nearest brick, and a body, D', extending rearward, 110 which fits against the side of said brick, substantially as set forth.

5. A curbstone or pavement block, in combination with a gutter of bricks arranged in an inverted arch, and a locking-piece which fits on the front and bottom of said curbstone or block and on the front side and rear of the nearest brick, substantially as set forth. 115

In testimony whereof I affix my signature in presence of two witnesses.

ISRAEL L. LANDIS.
